UNITED STATES PATENT OFFICE.

FRANK W. MOORE, OF REDLANDS, CALIFORNIA.

GAS COCK OR VALVE.

Application filed March 22, 1926. Serial No. 98,516.

This invention relates to gas-cocks or valves, such as used on gas stoves for turning on the gas at the burners. In cooking with such stoves, it is frequently desired to use the largest possible flame of the burner for a short period, for example, where a food is to be boiled for a short time and afterwards left to simmer. Gas-cocks have been patented heretofore which were so constructed as to enable the gas to be turned "full on" or partially turned on, but as usually constructed for this purpose, the plug of the gas-cock was not held against a stop when in the "off" position, that is to say, such devices have been constructed in such a way that the lever or handle was left in an intermediate position when the gas was off and from this position, the handle could be turned in two directions, in one of which the rotation of the plug was not stopped until the plug was in the "full on" position; but if the handle was rotated in the other direction, another stop would hold the plug so that the valve would be turned partially on. A valve of that construction does make it possible to apply the full heat of the burner first, and thereafter turn the gas down to the "simmering" position for the burner. However, a gas-cock of the construction just described is objectionable for the reason that the plug is not up against a stop when it is in its "off" position and hence in using a stove with a gas-cock of that construction, the cook must take care to leave the valve in the "off" position, that is to say, in a position so that no gas is leaking past the valve. As is well known, the plugs of gas-cocks frequently become very loose which renders them unsafe due to the danger of leaving them in a leaking position by a person who believed that he had left the gas completely turned off.

The general object of this invention is to produce a gas-cock which will perform the functions of the gas-cock described above, but constructed in such a way that it can be operated with safety.

Further objects of the invention will appear hereinafter.

The invention consists in the novel parts and combinations of parts to be described hereinafter, all of which contribute to produce an efficient gas-cock or valve.

A preferred embodiment of the invention is described in the following specification,

while the scope of the invention is pointed out in the appended claims.

In the drawing:

Figure 1 is a front elevation of a gas-cock embodying my invention.

Figure 2 is a horizontal section through the gas-cock and showing the same in the "off" position. This section is taken on the line 2-2 of Figure 1, looking upwardly.

Figure 3 is a view similar to Figure 2 but showing the gas-cock in the "full on" or completely open position.

Figure 4 is a view similar to Figure 3 but showing the gas-cock in its partially open position, enabling the gas to be left partially on.

In practicing my invention, I provide a body and a rotatable plug with cooperating gas ports; the body has a fixed stop which cooperates with a stop member which is mounted to move with the plug. In one position of the valve or plug, the stop member of the plug engages the fixed stop and stops the valve or plug in the "off" position. By rotating the handle, the plug will be rotated in a direction to bring the gas-cock to its "full on" position with the gas ports in full communication; and by rotating the handle further in the same direction, the plug will come up against a second stop that stops the plug in a slightly open position such as will supply enough gas to let the food simmer.

Regarding the invention from another angle, it may be said that I provide a handle for the plug which is in an intermediate position when the valve or gas-cock is "full on" and by moving the handle in one direction from this intermediate position, the plug will come up against a stop holding the valve turned off; if rotated in the other direction, the plug will come up against a stop which stops the ports in partial communication, that is, the valve is partially open.

Referring to the preferred embodiment of the invention illustrated in the drawing, 1 indicates the body of the gas-cock which is provided with a rotatable plug 2 of common type and capable of being rotated by a handle 3. The body and plug have gas ports 4 and 5 which align with each other when the gas-cock is in its "full on" position, as indicated in Figure 3.

At a suitable point, the body of the valve

is provided with a fixed stop which may be in the form of a shoulder or radial face 6. The plug 2 of the valve is provided with a stop member or pin 7. When the gas-cock 5 is in its "off" position, as illustrated in Figure 2, the stop member or pin 7 is up against the shoulder 6.

When the gas-cock is in its "full on" position, as illustrated in Figure 3, the plug is not up against a stop but is in a position such that the pin 7 is at an intermediate point between the stop 6 and a second stop or shoulder 8 carried by the valve body at a point beyond the location of the stop pin 7. In other words, in turning the valve on, the handle 3 is moved in the direction indicated by the arrow in Figure 2, until the handle arrives at the position shown in Figure 3. In order to partially close the valve, the handle should be rotated further in the same direction until the stop pin 7 strikes the shoulder 8. In this position, the valve will be partially on, that is to say, the gas ports will be in partial communication, as illustrated in Figure 4.

A gas-cock or valve having these features of construction is safe when handled by a child or a careless person because in turning the gas off from the "full on" position or from the "partially on" position, the handle is turned in the same direction and it would naturally be turned until it comes up against the stop 6. The gas cannot be turned out and then on again unlighted as is possible with some gas-cocks having the partially open position. In other words, with my construction of gas-cock, when the gas is off, the plug is up against a stop, and in turning the gas-cock to the partially on or "simmering" position for the valve, the handle must be rotated beyond the "full on" position.

Associated with the stop shoulder 8, I provide a longitudinally adjustable stop-member, the end face of which is engaged by the pin 7 carried on the valve plug. This adjustable stop is preferably in the form of an adjustable set screw 9. This set screw is mounted in the casing or body 1 of the valve and its head is exposed on the exterior. One of the advantages of this construction is that this stop can be adjusted while the gas is lit with a small simmering

flame; in other words, by holding the pin 7 up against the adjusting screw 9 and adjusting this screw, the small flame can be regulated as desired while the flame is burning.

What I claim is:

1. In a gas-cock, the combination of a body and a rotatable plug with cooperating gas ports, said body having a fixed stop on the said body, a single stop member mounted to move with the plug for engaging the fixed stop in the "off" position of the gas-cock, a handle for rotating the plug in a direction to bring the gas-cock to its "full on" position with the gas ports in full communication, said body having a second stop beyond the position of the stop-member in the "full on" position of the gas-cock and cooperating with the stop-member when the plug is rotated further in the same direction to hold the gas ports in partial communication, to produce a small flame, said second stop-member being constructed to be adjusted longitudinally and mounted so that its end face abuts against the stop-member on the plug, and accessible from the exterior of the valve to enable the size of the small flame to be regulated.

2. In a gas-cock, the combination of a body and a rotatable plug with gas ports, a handle for the plug, said plug and body cooperating in the "on" position of the handle to hold the ports in full communication, a single stop-member mounted to move with the plug, said body having a fixed stop cooperating with the stop-member when the handle is moved in one direction from the said "on" position into the "off" position, and a second relatively fixed stop to engage the stop member when the handle is moved in the other direction from the "on" position, and operating to hold the gas ports in partial communication, to produce a small flame, said second relatively fixed stop consisting of a screw mounted in the valve casing for longitudinal adjustment, with its end face in position to engage the single stop-member carried by the plug, and accessible from the exterior of the valve to enable the size of the small flame to be regulated.

Signed at Los Angeles, Calif., this 9 day of March, 1926.

FRANK W. MOORE.
